BATHROOM WALL PANEL

Merritt W. Seymour, Sylvania, Ohio, assignor to Owens-Corning Fiberglas Corporation

Filed Nov. 21, 1972, Ser. No. 308,373

Term of patent 14 years

Int. Cl. D23—02

U.S. Cl. D23—69

FIG. 1 is a front elevational view of a bathroom wall panel embodying my new design;

FIG. 2 is a side elevational view thereof;

FIG. 3 is a cross sectional view taken on line 3—3 of FIG. 1; and

FIG. 4 is a top plan view thereof.

I claim:

The ornamental design for a bathroom wall panel, substantially as shown.
